UNITED STATES PATENT OFFICE.

WILLIAM C. POOLE AND JOHN SCHNEPF, OF NEW YORK, N. Y.

ELECTRICAL ANNUNCIATOR.

SPECIFICATION forming part of Letters Patent No. 367,925, dated August 9, 1887.

Application filed December 18, 1886. Serial No. 221,917. (No model.)

To all whom it may concern:

Be it known that we, WILLIAM C. POOLE and JOHN SCHNEPF, both of the city, county, and State of New York, have invented certain new and useful Improvements in Electrical Annunciators; and we do hereby declare that the following is a full and exact description thereof, reference being had to the accompanying drawings, and to the letters of reference so marked thereon, making a part of this specification, in which—

Figure 1 is a side elevation, in perspective, of our improved electrical annunciator; and Fig. 2, a vertical longitudinal section of the same.

Our invention relates to that class of annunciators in which the drop or index plate constituting the visual signal is thrown out of its concealed position and brought to view by the movement of the armature of an electro-magnet when the latter is excited by an electric current.

In the annunciators of this class as heretofore constructed the pivoted signal, or index-plate or drop, when actuated by the movement of the armature, turns upon its pivot in an arc of ninety degrees or more, so as to drop from an upright or rearwardly-inclined position, wherein it remains normally concealed from view, to a vertical pendent position in which its rear face bearing the signal character is brought to sight. The action of the armature in this case serves merely to move the plate out of the perpendicular far enough to allow it to swing forward and turn over by its gravity, to bring to view its rear face bearing the signal number, word, or letter. In these annunciators the index-plate must necessarily be light and small, and be mounted so far back of the glass face of the case in which it is placed as to allow space for the plate to turn upon its axis and clear the glass in its movement, and when the plate has thus turned over into view it must be lifted and turned up into its first position mechanically, while if, as is often the case, the armature becomes polarized, so as to remain in contact with the magnet after it has actuated the index-plate, the armature must likewise be mechanically detached before the plate can be returned to its normal position.

The object of our invention is not only to

simplify and reduce the cost of these electrical annunciators, but to so construct them as to bring the index or signal plate into close proximity to the glass-covered opening in the case, 55 and cause said plate to drop out of sight automatically by its gravity so soon as the armature is released from the magnet, and to so counterbalance the plate and armature as that a plate of any desired size may be actuated by 60 a comparatively weak current or a small magnet.

We have attained our object by the construction of an annunciator, as hereinafter described, in which the pivoted index or signal 65 plate lies normally out of sight in a horizontal plane, into which it falls automatically by its gravity when left free, and is pushed up and held in a vertical position, so as to bring its face to view against the glass face of the case, 70 by means of a pin or rod actuated by the pivoted armature of a magnet whose frame and core are made of cast-iron or steel and permanently magnetized, so as to hold the armature automatically after it has been attracted 75 thereto until it is mechanically released therefrom by suitable means, the pivoted armature being furthermore counterbalanced so that it will easily lift the index-plate, even though it be of large size.

In the accompanying drawings, Figure 1 is a perspective view, and Fig. 2 a sectional view, of my annunciator.

A represents the frame by which the electro-magnets, the vibrating armature, and the index-plate for the annunciator are supported. This frame is made of cast-iron or steel, and the cores B B for the electro-magnets C C are cast in one piece with the frame. The armature D is also made of cast-iron or steel, and is 85 formed integrally with an arm or lever, E, pivoted to the lower portion of the frame A, as shown in Fig. 1, so that the armature may freely vibrate to and from the magnets C C. The magnets are preferably mounted in a vertical position, their supporting frame A being secured by a screw, F, to the case of the annunciator, or to a standard, G, so that the armature-lever shall swing in vertical plane and maintain a nearly horizontal position beneath 90 the magnets.

An index-plate or signal-tablet, H, of suit-

able dimensions is pivoted at one edge to the top of the frame above the cores B B of the magnets, so as to drop flat into a horizontal position over said top plate of the frame and be thereby concealed from view, (see Figs. 1 and 2,) and swing up therefrom into a vertical position, to thereby bring its upper front face fully to view above the magnet. (See dotted lines in Fig. 2.)

- 10 A rod or pin, J, is carried vertically through an aperture in the top plate of the frame, immediately back of the pivotal axis of the index-plate, and, passing down between the electro-magnets C C, rests upon the armature D, while its upper end is brought to bear against said index-plate H close to its pivotal axis. The rod is so proportioned in length as that when the armature D is released and drawn away from the magnets the upper end of the rod will drop far enough to allow the index-plate H to fall over into a horizontal position, as shown by the positive lines in Fig. 2; but when the armature is drawn up against the magnets the rod is lifted sufficiently to turn the index-plate up into a vertical position, as indicated by the dotted lines in Fig. 2, and there support it.
- 15
- 20
- 25

In order to steady the movement of the rod or pin J, it is preferably inclosed in a tube, L, which is made fast to the top plate of the frame A, to depend therefrom, as shown in Fig. 2. The upper end of the rod J is fitted with a rounded head or button, M, so as to reduce its friction with the index-plate as it operates to force the latter up.

30 The index-plate is prevented from tipping or dropping forward by means of a stop, K, or by striking against the glass plate which covers the opening in the front plate of the annunciator-case, through which the index-plate is exposed to view when thrown up.

35 A weight, P, is affixed to the shorter arm of the armature-lever E beyond its pivot, so as to counterbalance the weight of its longer arm and of the armature D and rod J, carried thereby, and thereby leave the armature free to move toward the electro-magnets under a very slight impulse; hence but a comparatively slight current will suffice to produce the attraction needed to draw the armature into contact and thereby lift the index-plate.

40 The cast-iron frame A and the cores B B, formed in one piece therewith, as also the armature D, are permanently magnetized, so that when the armature D is drawn into contact with the magnets C C it will remain in contact therewith after the current through the coils of the magnets is interrupted or cut off, and thereby hold the rod J up in position to support the index-plate H in its upright position exposed to view. So soon as the armature is released from the magnets and drops away therefrom, the rod J, dropping with it, will leave the index-plate unsupported and free to swing back by gravity into its normal horizontal position out of view. The release of the armature D may be effected mechani-

50 cally in various ways—as, for example, by a crank-shaft, R, fitted to bear against the lower end of the weight P, which depends from the inner end of the lever E at a right angle thereto. The crank being brought to bear against the weight, to force it rearwardly, will cause the lever to turn upon its axis and draw the armature down away from the magnets.

55 It is evident that the weight may be cast or formed in one piece with the lever E, and that it may also be fitted to the inner end of the lever in the rear of the frame A, at x, instead of depending therefrom. The instrument will be thereby rendered more compact, and we contemplate so constructing the instrument.

60 The rod J is preferably permanently magnetized, so as to be held by magnetic attraction in contact with the armature and thereby positively drawn down with the armature when it drops.

65 In the use of the annunciator constructed as described, when the electric circuit is closed through the wires S S' by the occupant of a room whose number is indicated on the plate H, the electro-magnets, becoming excited, will attract and lift the armature D.

The rod J will be thereby elevated, and its upper end, bearing against the pivoted plate H, will turn it into a vertical position, as indicated by dotted lines in Fig. 2, so that its face bearing the numeral corresponding to the number of the room will become visible through the glass-covered opening in the case containing the instrument. The upper edge of the index-plate striking the glass, or a stop, K, in place thereof, will be prevented thereby from falling forward, while the pin J will be kept in its elevated position back of the plate, to prevent it from dropping backward by reason of the attraction of the permanently-magnetized cores B B for the armature.

70 The armature D is withdrawn from the magnets and the index-plate consequently allowed to drop back automatically after it has been seen and noted by rotating the crank-rod R so as to bring the crank to bear against the weight and thereby move the armature-lever away from the magnet, so that the rod J may drop. When the rod J drops, the weight of the free end of the pivoted index-plate will cause it to fall over out of sight into its horizontal position, as shown by the positive lines in Figs. 1 and 2.

75 The entire instrument is very compact, and being constructed of the fewest possible parts—viz., the frame and cores cast in one piece, the armature and its lever cast in another piece, the index-plate made of sheet metal, the spools fitted upon the cores to complete the magnets, and the elevating-rod, all united in simple manner—its cost is reduced to a minimum. It obviates, also, wholly the disadvantages attendant upon the trips and catches used in other forms of annunciators. As the index-plate is held positively in position when brought to view, it cannot drop back under the effects of a jar or blow, but will remain in

sight until allowed or caused to drop by the operator.

We claim as our invention—

1. The combination of a permanently-magnetized core with the electro-magnet of an annunciator, its vibrating armature, an index-plate pivoted above the magnet to drop by gravity into a horizontal position out of sight, and a rod interposed between the armature and index-plate, operating, when the armature is attracted by the magnet, to throw the index-plate up into sight in a vertical position and there support it, substantially in the manner and for the purpose herein set forth.
- 15 2. The combination, with the electro-magnet, in an electrical annunciator, of the cast-iron supporting-frame formed integral with the core or cores of the electro-magnets, the cast-iron armature and lever formed in one piece and pivoted to said frame, the index-plate likewise pivoted to the frame, and the rod actuated by the armature and actuating the index-plate, all substantially in the manner and for the purpose herein set forth.
- 20 25 3. The combination, in an electrical an-

nunciator, with the pivoted index-plate, the pivoted armature-lever and armature, and a rod or pin interposed between the armature and index-plate, of a weight attached to or formed upon the shorter arm of the vibrating lever to counterbalance the weight of its longer arm and armature, and of the rod and index-plate supported thereby, substantially in the manner and for the purpose herein set forth.

4. The combination of an electro-magnet, a pivoted armature-lever and armature, and a pivoted index-plate adapted to drop out of sight by gravity, of a magnetized rod interposed between the armature and index-plate to be held or jointed to the armature by magnetic attraction, substantially in the manner and for the purpose herein set forth.

In testimony whereof we have signed our names to this specification in the presence of two subscribing witnesses.
